DESIGN FOR A DRESS

Johnnye Lee Caston, Chicago, Ill., assignor to
The Sterling Company, Chicago, Ill., a Corporation of West Virginia

Application July 1, 1933. Serial No. 48,616

Term of patent 3½ years

To all whom it may concern:

Be it known that I, JOHNNYE LEE CASTON, a citizen of the United States, residing at Chicago, in the county of Cook and State of Illinois, have invented a new, original, and ornamental Design for a Dress, of which the following is a specification, reference being had to the accompanying drawing, forming a part thereof.

Fig. 1 is a perspective front view of a dress embodying my design; and

Fig. 2 is a perspective rear view on a reduced scale of the dress shown in Fig. 1.

I claim:

The ornamental design for a Dress as shown. In witness whereof, I hereunto subscribe my name this 29 day of June, 1933, at Chicago, Illinois.

JOHNNYE LEE CASTON.
